POLYGONAL DRINKING FOUNTAIN

Allen C. Wright, Moraga, Calif., assignor to Haws
Drinking Fountain Company, Berkeley, Calif.

Filed Nov. 30, 1970, Ser. No. 26,232

Term of patent 14 years

Int. Cl. D23—01

U.S. Cl. D67—4

FIG. 1 is a perspective view of a polygonal drinking fountain embodying the invention looking downwardly toward the top thereof.

FIG. 2 is a top plan view thereof.

FIG. 3 is a side view in elevation looking directly toward one corner portion of the drinking fountain.

FIG. 4 is a front view in elevation thereof.

FIG. 5 is a side view in elevation of the fountain looking toward the opposite corner portion from that shown in FIG. 3.

FIG. 6 is a fragmentary rear view in elevation of the fountain.

I claim:

The ornamental design for a polygonal drinking fountain, substantially as shown.
